UNITED STATES PATENT OFFICE.

JULIUS A. PIERSON, OF WINLOCK, WASHINGTON.

LOGGING-CARRIAGE.

1,384,848.

Specification of Letters Patent. Patented July 19, 1921.

Application filed December 31, 1920. Serial No. 434,281.

To all whom it may concern:

Be it known that I, JULIUS A. PIERSON, a citizen of the United States, residing at Winlock, in the county of Lewis and State 5 of Washington, have invented certain new and useful Improvements in Logging-Carriages, of which the following is a specification.

This invention relates to a logging carriage of that class which is used with logging apparatus in which cable ways are employed for the transportation of logs from place to place.

One object of the invention is to simplify 10 and improve the construction and operation of the carriage which is employed for conveying the load.

A further object of the invention is to provide simple and efficient means for greasing 15 the cable and lubricating the journals of the sheaves or supporting wheels.

A still further object of the invention is to provide means for holding the carriage while the logs are being held at the spar 20 tree which is usually at the top of a steep grade.

With these and other ends in view which will readily appear as the nature of the invention is better understood, the same consists 25 in the improved construction and novel arrangement and combination of parts which will be hereinafter fully described and particularly pointed out in the claims.

In the accompanying drawings has been 30 illustrated a simple and preferred form of invention, it being, however, understood that no limitation is necessarily made to the precise structural details therein exhibited, but that changes, alterations and modifications 35 within the scope of the claims may be resorted to when desired.

In the drawing:—

Figure 1 is a side elevation of the carriage,

Fig. 2 is an end elevation thereof parts 40 being shown in section,

Fig. 3 is a fragmental view showing the construction of the automatic holding device used in connection with the carriage,

Fig. 4 is a similar view, and

Fig. 5 is an elevational view of one of the gripping jaws.

Referring to the drawings in detail it will be seen that the carriage is preferably formed of the two parallel spaced apart side walls 5 which are suitably connected together by rivets or bolts and may have por-

tions thereof removed for lightening the device if so desired. In order to efficiently brace the plates 5 a frame 6 is arranged around the edge of each plate and may be 60 substantially rectangular in shape and preferably formed from angle iron and is riveted or bolted to each plate. At the upper corners of the carriage suitable sheaves or supporting wheels 7 are provided and are 65 constructed with the stub axles 8 which protrude in journal boxes 9. These journal boxes are provided on each of the plates 5. Each journal box 9 is constructed so as to include an upper compartment 10 and a lower compartment 11. The upper compartment 10 is provided with suitable openings so that oil may be inserted therein and this compartment 10 will communicate with the compartment 11 through an aperture or a series 70 of apertures. The usual waste is packed into the compartment 11 so as to be saturated from the oil in the compartment 10. A journal bearing block 12 is disposed between the upper tank 10 and the stub axle 80 8 in each lower compartment 11 and is held in place by means of a transverse pin 13 which prevents lateral movement of the block 12. By removing this pin 13 it will be readily seen that this block may be easily 75 removed. Any suitable closure means may be provided for the lower compartment 11 if so desired or it may be left open as is shown at 14 so that the bearing block 12 may be pushed therethrough. A tank 15 is 85 disposed between the plates 5 intermediate the sheaves 7 and is provided with a plurality of fountain brushes 16 which are in communication therewith through pipes 17. These fountain brushes 16 are arranged so 90 as to sweep or brush over the cable 17 and a lubricant will be provided in the tank 15 so that this cable 17 may be greased as is very 95 desirable in a logging apparatus. In one of the lower corners of the frame or carriage a suitable swivel 18 is provided to which is attached the hauling rope or cable and in the other corner a pulley 19 is provided for hoisting and lowering the load by means of a rope or cable 20 passing there- 100 over.

At the end of the carriage in which is provided the pulley wheel 19 a plate 21 is provided for supporting a housing 22 which is an extension to the carriage. This housing 22 comprises two spaced apart plates having arcuate slots 23 therein for receiving

pins 24 on the plate 21 so that this extension may move pivotally in relation to the plate 21. A sheave 25 is suitably journaled in the extension so as to bear on the cable 17. An 5 automatic holding device is held in the extension and includes the oppositely disposed housings 30 having slidably mounted there-in blocks 31 which form jaws for a purpose which will be later described. These jaws 31 10 are slidable in the housings 30 and are normally in engagement with each other as shown in Fig. 3 by means of the expansion coil spring 32 which may be suitably tensioned through the screws 33. A grip or 15 stop 34 is fixed to the cable 17 adjacent the spar tree where it is desired to unload the logs which is usually at the top of a steep incline and as the carriage is moved on the incline it passes over the grip or stop 34 and 20 it should be noted that this stop 34 has its ends tapered so that the jaws 31 are opened as they pass thereover. After the jaws have completely passed over the stop 34 the carriage will not automatically return to the 25 loading position until it is so desired. In the devices now commonly in use when a turn of logs is being hauled in over a steep grade on the sky line and dumped at the spar tree the ordinary carriage always runs 30 back by its own weight thereby tightening the line which is to be unhooked. Because of my automatic holding device just described the carriage will be held in position when the load is dropped thereby allowing 35 enough slack in the line for unhooking. When the carriage comes in with a load the sudden pressure against the grip causes the jaws which are held pressed against each other by means of the springs 32, to open 40 and then again close when the jaws have passed over the grip. After the carriage

has come to a stop and runs back to the grip it will not have sufficient momentum to cause the jaws to open and it will require the pull of the back line to release the carriage from the grip. As the jaws hit the stop or grip the carriage comes momentarily to a stop thus preventing the whole carriage from passing over the grip. This automatic holding device is attached to the carriage through the means of the extension 22 45 and because of the movable relation of this extension with the carriage the holding device is sure to be in perfect alinement under all working conditions and angles of the sky line by means of the sheaves 25 and the arcuate slots 23 working on the pins 24. These arcuate slots 23 are concentric with each other so as to have a common center and it will therefore be seen that the extension 22 50 is really pivoted or rather in pivotal relation with the carriage.

Having thus described my invention what I claim as new is:—

1. In combination, a logging carriage, a 55 housing pivotally associated therewith, a sheave journaled within the housing, and an automatic holding device situated within the housing for the purpose specified.

2. In combination, a logging carriage, a 60 housing pivotally associated therewith, a sheave journaled in the housing, a pair of oppositely disposed blocks carried slidably in the housing, means for holding the blocks normally in engagement with each other. 75

In testimony whereof I affix my signature in presence of two witnesses.

JULIUS A. PIERSON.
